UNITED STATES PATENT OFFICE

163,023

TIE CLASP OR SIMILAR ARTICLE

Kathy R. Cassel, Chicago, Ill.

Application October 25, 1950, Serial No. 12,710

Term of patent 14 years

(Cl. D17—3)

To all whom it may concern:

Be it known that I, Kathy R. Cassel, a citizen of the United States of America and residing in the city of Chicago, county of Cook, and State of Illinois, have invented a new, original, and ornamental Design for a Tie Clasp or Similar Article, of which the following is the specification, reference being had to the accompanying drawings, forming a part hereof:

On the drawings:

Fig. 1 is a front elevational view of a tie clasp embodying my new design; and

Fig. 2 is a top plan view thereof.

I claim:

The ornamental design for a tie clasp or similar article, substantially as shown.

KATHY R. CASSEL.
